UNITED STATES PATENT OFFICE

106,534

DESIGN FOR A TEXTILE FABRIC

Benjamin Gold, New York, N. Y.

Application August 17, 1937, Serial No. 71,144

Term of patent 3½ years

To all whom it may concern:

Be it known that I, Benjamin Gold, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein,

The figure is a plan view of a piece of textile fabric showing my new design.

The design is characterized by the combination on the fabric as shown, of striped areas superimposed by characters resembling shorthand hooks, as shown. The dot and dash lines on the drawing outline substantially a design unit, which unit is repeated in regular succession as indicated by the extensions beyond the unit boundaries.

I claim:

The ornamental design for a textile fabric, substantially as shown, and described.

BENJAMIN GOLD.
